UNITED STATES PATENT OFFICE.

EDWARD L. JONES, OF DOVER, DELAWARE, ASSIGNOR TO ARTHUR B. HUEY, OF PHILADELPHIA, PENNSYLVANIA.

AUTOMATIC THROW-OFF AND CYLINDER-ADJUSTING MECHANISM FOR ROTARY PRESSES.

1,174,989.

Specification of Letters Patent. Patented Mar. 14, 1916.

Application filed April 28, 1908, Serial No. 429,636. Renewed August 8, 1914. Serial No. 855,905.

To all whom it may concern:

Be it known that I, EDWARD L. JONES, a citizen of the United States, residing at Dover, in the county of Kent and State of Delaware, have invented certain new and useful Improvements in Automatic Throw-Off and Cylinder-Adjusting Mechanism for Rotary Presses; and I do hereby declare the following to be a full, clear, and exact description of the invention, such as will enable others skilled in the art to which it appertains to make and use the same.

This invention is more particularly adapted for rotary printing-presses used in connection with an automatic sheet-feeder, or other rotary sheet-printing presses, such for example as web-presses where the paper-web is cut into sheets which are successively taken on an impression-cylinder. In a broader aspect, however, the invention has a wider range of adaptability to various types of sheet-printing presses and designed to allow the type and impression surfaces to be thrown off or on impression.

The term "rotary press" is employed herein to signify any printing-press having a rotary (including oscillatory) impression-cylinder coöperating with a printing-form on any well known type-carrier. The particular species of press herein selected for illustrating the invention is a two cylinder job-press, comprising continuously revolving type and impression cylinders, and equipped with an automatic sheet-feeder which is made the subject-matter of my companion application filed April 28, 1908, Serial No. 429,635.

The main object of the invention is to provide improved trip-mechanism for preventing the printing operation of the press by automatic throw-off of the impression-cylinder without arresting its rotation, so as to overcome the liability of spoiling the impression-surface or tympan by repeated contact with the printing-form, when the supply of sheets has become exhausted or when for any cause the grippers of the impression-cylinder fail to take a sheet.

A further object is to provide improved means for adjusting the shaft of the impression-cylinder for paralleling the type and impression surfaces when the printing-form

(particularly the stereotype plate used on a rotary type-cylinder) is higher at one end than at the other end, so as to avoid the necessity of extra underlays or packings with concomitant difficult adjustments to obtain a uniform or even impression.

The invention will hereinafter be fully described by reference to the accompanying drawings, which form a part of this specification, and then more particularly pointed out in the appended claims.

In said drawings: Figure 1 is a side view of a rotary press embodying my invention. Fig. 2 is a perspective view of the shaft of the impression-cylinder and its bearings. Fig. 3 is an end view of the bearing for the cylinder-shaft, looking at the opposite side of the press from that illustrated in Fig. 1. Fig. 4 is a diagrammatic front view of the press showing the electrically-controlled means for actuating the throw-off. Fig. 5 is a detail of one of the grippers open. Fig. 6 is a detail of said gripper closing on a sheet of paper, which is indicated as insulation. Fig. 7 is a detail of said gripper closed in the absence of a sheet of paper.

In the drawings, the press-mechanism is shown in an appropriate frame A constructed upon a pedestal-base.

B denotes the type-cylinder on which is fixed the stereotype plate constituting the printing-form.

C denotes the impression-cylinder which is provided with the usual tympan forming the impression-surface and which carries sheet-grippers.

F indicates an automatic sheet-feeding attachment which is fully set forth in my said copending application. It comprises, in general terms, an upper reciprocating feed-table and lower registering-table. The reciprocating feed-table, operating in conjunction with a pneumatic sheet-separator, feeds the sheets to coacting-feed-rolls which deliver it upon the registering-table, from which the sheet is taken by the grippers of the impression-cylinder, in a manner well understood by those skilled in the art.

Motion is communicated from the drive-shaft 1 having a pinion 2 meshing with gear 3 which in turn meshes with gear 4, whereby the type and impression cylinders are

caused to revolve oppositely and at the same speed. Pinion 2 also meshes with gear 5 on a shaft 6 whose special function in connection with this invention will appear later. 5 Gears 3, 4 and 5 are of equal size. Power for running the press is applied by a belt (not shown) adapted to be shifted by a controlling lever 7 from loose pulley 8 to fast pulley 9 on the drive-shaft 1 (Fig. 4). 10 The axis of the impression-cylinder is capable of shifting to effect the throw-off. As a preferred means for this purpose, the shaft 10 on which the impression-cylinder revolves is eccentric from its trunnions which are journaled in the opposite sides of the frame 15 of the press. On one end or trunnion of said shaft is affixed a throw-off device or crank 11. The crank 11 is shown depending and provided with a rearwardly-extending elbow-arm 12 which has an inwardly-extending arm 13. A strong pull-spring 14 inside the frame, having one end attached to the frame and the other end secured to the arm 13, holds the impression-cylinder in its normal relation to the type-cylinder. 20 A set-screw 15, tapped through the arm 13 and abutting the rear of the frame, limits the position of the cylinder under pull of its spring and makes this position adjustable for light or heavy work. 25 On the shaft 6 is a cam 16 which works against a friction-roller 17 carried by a reciprocating member, preferably a slotted link 18, which slides back and forth on guide-blocks 19 and 20 carried by the arm 12 of the crank 11. Said slotted link is reciprocated in one direction by the cam 16 and in the opposite direction by a pull-spring 21 having one end attached to the 30 frame and its other end fastened to the link. Said link 18 carries in a suitable case an electro-magnet 22 whose armature 23 controls a movable trip-pin 24 working in a hole in the link. When the magnet is energized the pin 24 is thereby caused to project into the slot of the link in front of one of the guide-blocks, preferably the front block 19; and on demagnetization the pin retracts. 35 In the construction illustrated, the magnet is shown attached to the bottom of the link and its armature is arranged to lift and drop the pin, which constitutes a trip for engaging a stop (block 19) on the crank 11. According to whether the magnet is energized or not, the slotted link 18 will at each reciprocation rock the crank and thereby throw-off the impression cylinder from the form cylinder without disconnecting their intergeared connections, or 40 it will simply reciprocate inoperatively on the guide blocks 19 and 20.

A battery 25, of preferably dry cells, is contained in a chamber in the base of the press. Circuit wires from the battery are indicated by the letters *a* and *b*. One insu-

lated circuit wire *a* leads to one pole of the magnet, there being a switch *c* interposed. The other pole of the magnet is grounded to the iron of the machine. The other insulated circuit wire *b* leads to binding post *d* 75 which is in electrical connection with a segmental track *e* opposite one end of the impression-cylinder; said track *e* being insulated from the iron of the machine. The impression-cylinder has in its surface an insulated pin or plunger *f* which projects through a hole in the tympan and is so located that one of the gripper fingers *g* will close upon it. Said plunger *f* is connected by an insulated wire *h* with another insulated pin or plunger *i* in the end or head of the cylinder, which plunger *i* is adapted to contact with the segmental track *e*. The switch *c* has an insulated connection with the belt-shifting lever 7, whereby the switch is opened and closed according to whether the controlling lever throws the belt to the loose or fast pulley; in other words the switch is closed only when the power is applied for running the machine. 90

Assuming that the machine is running and the switch closed, the operation is as follows: During each rotation of the impression-cylinder, if its grippers take a sheet from the registering-table of the feeder, the sheet of paper so taken insulates the gripper finger *g* from the plunger *f*, as indicated in Fig. 6, so that the electric circuit remains open, and hence the trip or pin 24 remains down and allows the slotted link 18 to reciprocate inoperatively. Hence, so long as the sheets are successively supplied to and taken by the impression-cylinder, said impression-cylinder is maintained in its normal relation to the type-cylinder for making the impression. But if the grippers as they close fail to take a sheet, the electric-circuit is closed by the gripper *g* closing down on the plunger *f*, as indicated in Fig. 7, the gripper being connected to one pole of the magnet 100 22 through the iron of the machine, and the plunger *f* being connected by the wire *h* to the plunger *i* which contacts with the track *e* which latter is in connection through the circuit-wires and battery with the other pole of the magnet. The closing of the circuit energizes the magnet whose armature projects the pin or trip 24 in front of the stop or block 19, whereby on backward throw of the link 18 the crank 11 is rocked to throw out the impression-cylinder sufficiently to separate its impression-surface from the printing-form on the type-cylinder and without disconnecting their intergeared connections 3 and 4, the impression-cylinder being returned by its pull-spring 14. So long as the supply of paper is exhausted, or until the grippers take a sheet, the impression-cylinder will thus be thrown out and returned at each rotation. To express it 110 120 125 130

briefly, during the phase of rotation while the pin or plunger *i*, constituting a contact point, rides on the segmental track *e*, the gripper *g* and pin or plunger *f* constitute terminals of an open electrical circuit, which is adapted to be closed only if the gripper closes on said plunger *f*, but, said circuit will remain open if a sheet of paper is received, since the paper insulates said terminals.

10 At preferably the side of the press opposite the throw-off device, one end or trunnion of the eccentric shaft 10 is journaled in an eccentric bushing 26 having an arm 27 provided with a short segmental slot through which is inserted a screw-bolt 28 for rigidly fastening the arm. On loosening the screw-bolt 28, the arm 27 can be angularly-adjusted, thereby changing the center of the eccentric-bushing 26 for axial adjustment of the shaft 10 on which the impression-cylinder revolves.

This device provides a convenient mode of paralleling the impression-surface and printing-form to secure an even or uniform impression longitudinally.

Having thus described my invention, what I claim as new and desire to secure by Letters Patent of the United States is:

1. In a printing-press, the combination of a rotary impression-cylinder and coacting printing-form, throw-off mechanism comprising an axis-adjusting crank for said cylinder, a reciprocatory member carrying a normally-inoperative trip, an electro-magnet controlling said trip, gripper fingers and means for energizing said magnet controlled by the grasping of sheets by the gripper fingers to allow the trip to throw said crank only when no sheet is taken by the gripper fingers.

2. In a printing-press having gripper fingers, a throw-off mechanism comprising a throw-off or adjusting crank, a link mounted to reciprocate on said crank, a movable trip carried by one of them adapted when protracted to engage a stop on the other and thereby cause simultaneous and equal movement of the link and the crank, and automatic means for controlling said trip operated by said gripper fingers.

3. In a printing press, a rotary impression cylinder, a printing form coacting therewith, an eccentrically journaled shaft for said cylinder, a crank upon said shaft and formed with an arm provided with guide-blocks, yielding means connected to said arm to draw the same in one direction, a slotted link slidable upon said guide-block, means for reciprocating said link, a trip adapted to enter the slot of said link to engage a guide-block, an electro-magnet connected to move said trip into the slot of the link, a source of electricity having its circuit wires connected to said magnet, and a gripper upon the impression cylinder having

its members electrically connected to the circuit wires of the magnet and insulated from each other by grasping a sheet.

4. In a printing press, a rotary impression cylinder, a printing form coacting therewith, a shaft journaled at its ends and having the impression cylinder rotatable upon a portion eccentric to its trunnions, a crank upon one of the trunnions of said shaft and formed with an arm having guide-blocks, a spring connected to said arm to draw it and the crank in one direction, a slotted link slidable upon said guide-blocks, means for reciprocating such link, a trip adapted to enter the slot of said link to engage a guide-block, a paper gripper upon the impression cylinder, and automatic electro-magnetic means for controlling said trip and connected to the members of said gripper.

5. In a printing press, the combination of a rotary impression cylinder and coacting printing-form, throw-off mechanism for effecting a relative movement between the said cylinder and form to bring them into and out of co-operative relation one with the other, said throw-off mechanism including a crank, a reciprocatory member for effecting the movement of the crank, a normally inoperative trip, an electro-magnet controlling said trip, gripper fingers, and means for energizing said magnet controlled by the grasping of a sheet by the gripper fingers to allow the trip to throw said crank only when no sheet is taken by the gripper fingers.

6. In a printing press, the combination of a rotary impression cylinder and coacting printing form, throw-off mechanism for effecting a relative movement between the said cylinder and form to bring them into and out of co-operative relation one with the other, said throw-off mechanism including a crank, a reciprocatory member for effecting the movement of the crank, a rotary cam for actuating said member, a normally inoperative trip, an electro-magnet controlling said trip gripper fingers, and means for energizing said magnet controlled by the grasping of a sheet by the gripper fingers to allow the trip to throw said crank only when no sheet is taken by the gripper fingers.

7. In a printing press, the combination with the intergeared form and impression cylinders one of which is mounted for movement toward and from the other to bring the cylinders into and out of co-operative printing relation without disconnecting their intergeared connections and without arresting the rotation of either cylinder, of a throw-off mechanism for shifting one of said cylinders relative to the other for the purpose specified, and electrically controlled operating means for said throw-off mechanism including an electro-magnet in a nor-

- 5 mally open circuit, an electric terminal on the impression cylinder included in said circuit, a gripper finger carried by the impression cylinder adapted to make contact with said terminal, said gripper finger constituting another terminal of said circuit, the construction and arrangement of parts being such that the circuit will be completed through the said magnet upon 10 the failure of a sheet to be gripped by the gripper finger, and thus separate the form and impression cylinders without disengaging their intergeared connections and without arresting the rotation of either cylinder.
- 15 8. In a printing press, the combination with the intergeared form and impression cylinders one of which is movable toward and from the other to bring the cylinders into and out of coöperative printing relation without arresting the rotation of either, of a throw-off mechanism for shifting one of said cylinders relative to the other for the purpose specified, said throw-off mechanism including a cam-operated reciproca- 20 25 tory link for positively moving the said
- shiftable cylinder, a normally inoperative magnetically controlled member for rendering the said link operative, a magnet for actuating said member, gripper-fingers carried by the impression cylinder for carrying the sheet to be printed into contact with the printing form, an electric circuit in which the said magnet is included, and an electric terminal carried by the impression cylinder with which one of the gripper fingers co-operates, whereby the circuit will be completed through the said magnet to actuate the magnetically controlled member upon the failure of a sheet to be gripped by the said gripper finger, and thus separate the 30 35 form and impression cylinders without disengaging their gears and without arresting the rotation of either cylinder.

In testimony whereof I affix my signature, in presence of two witnesses.

EDWARD L. JONES.
